UNITED STATES PATENT OFFICE.

ABNER JUDSON McGEHEE, OF JACKSON, TENNESSEE.

GASOLENE SERVICE-TANK.

1,383,135.

Specification of Letters Patent. Patented June 28, 1921.

Application filed August 30, 1919. Serial No. 320,763.

To all whom it may concern:

Be it known that I, ABNER J. McGEHEE, a citizen of the United States, and a resident of Jackson, in the county of Madison 5 and State of Tennessee, have invented certain new and useful Improvements in Gasoline Service-Tanks; and I do hereby declare the following to be a full, clear, and exact description of the invention, such as 10 will enable others skilled in the art to which it appertains to make and use the same.

My invention relates to an improvement in gasoline service tanks, the object being to provide a simple and inexpensive device 15 that will be absolutely reliable and quickly deliver a measured amount of gasoline to a motor car, the amount to be delivered being visible to the purchaser, and it consists in a graduated dispensing tank elevated so as to 20 deliver to the car by gravity, and means for elevating the gasoline from a larger reservoir, preferably located under ground, to the dispensing tank by the operation of compressed air, thus securing quick action and 25 dispensing altogether with the expensive pumping apparatus in common use for that purpose.

My invention further consists in the parts and combinations of parts as will be more 30 fully explained and pointed out in the claims.

The accompanying drawing is a view in vertical longitudinal section of my improved apparatus.

1 is the main reservoir, which in the present instance is shown under ground and 2 is a pipe leading from the main tank to a three way coupling 3, also underground. Communicating with the top of the coupling 3 is a pipe 4 which extends above the surface of the ground and is open at its upper end. Surrounding the open end of pipe 4 is the dispensing tank 6 preferably cylindrical in form and closed at its upper end 40 by the head 6^a, which is provided centrally with a threaded opening into which is screwed the nut 7 having a depending ring shaped beveled seat 7^a located immediately above the open end of pipe 4.

50 8 is a float preferably perforated and located within the tank 6 and provided with a central opening for the pipe 4 and with an upwardly projecting ring shaped valve 8^a conforming in diameter and position to the beveled seat 7^a on the nut and beveled at

its upper end to make a sealing joint with the beveled end of the seat 7^a. This valve 8^a snugly embraces the pipe 4 so as to prevent the passage of any appreciable quantity of gasoline down between it and the pipe, but 60 it should have a free sliding movement on the pipe so that it and the float 8 may rise and fall with the rise and fall of gasoline in the tank 6. The valve 8^a is of such length that when seated against its seat 7^a, 65 its lower end or the float carrying it, will be below the upper open end of the pipe 4 and thus shut off the flow of gasoline to the tank 6.

The tank 6 which is supported on the 70 stand 5, is graduated to indicate the contents in gallons, and is made of glass, or other transparent material, or is provided with an opening throughout its length covered with glass or other material, or with a 75 sight tube, so that the height of the contents of the tank will be clearly visible, and may be seen by the customers. This tank is seated on the top of stand 5 and may be 80 inclosed in a wire or perforated casing, or by bars to protect it against accidental blows, and is provided at its bottom with a reduced neck connected by coupling 9 with the discharge pipe 11, to which the discharge hose (not shown) is attached, the 85 pipe 11 being provided with a valve 10 for controlling the discharge of fluid from dispensing tank 6.

12 is a pipe leading from an air reservoir, compressor or other source of air under 90 pressure. This pipe 12 is preferably located underground and passes upwardly in stand 5 to a point within easy reach of the operator and then downwardly, under and into the three way coupling 3, its open end 95 being in a plane above the level of the connection of pipe 2 with the coupling and below and in the vertical plane of pipe 4. This pipe 4 is provided preferably in the bend at its upper end with the valve 13, this valve and the valve 10 being accessible 100 through a door 15 in the front of casing 5, so that when the door is locked the valves will be concealed and inaccessible.

Pipe 4 passes through coupling 9 attached 105 to the lower end of dispensing tank 6, and through the restricted opening in the lower end of said tank, ample space however being left around the pipe 4 for the passage of the gasoline to the discharge pipe 11. 110

All up to date service stations have a compressed air reservoir and pumps for it, for inflating tires, and I take advantage of such apparatus for supplying air to the gasoline dispensing apparatus.

Normally the dispensing tank is empty and gasoline stands in the pipes 4 and 12 up to the level of the gasoline in the main tank 1, the coupling 3 being always full of oil, hence when the air pressure is let into the vertical leg of pipe 12 by opening valve 13, the pressure acting on the column of gasoline forces it down pipe 12 and up pipe 4 and into tank 6, the gasoline in the main tank flowing into the coupling 3 as fast as the column is forced up the pipe 4 into tank 6. This tank 6 is marked to indicate gallons, in the present instance five, hence the operator by proper manipulation of the valve 13 can accurately control the flow of gasoline to the tank 6 and the customer can see the amount therein. If the operator fails to shut off the air at the time the tank 6 is filled to its measuring capacity, the float 8 will rise and cut off further flow to the tank, and when the air pressure is cut off by the valve 13 the gasoline in pipe 4 will seek its natural level and any gasoline in tank 6 above the top of pipe 4 will flow back into the latter. After the tank 6 has been charged with the proper amount of gasoline desired by the customer, the air is cut off and valve 10 opened thus permitting the gasoline or any part of it in the tank 6 to gravitate into the tank on the motor.

With this device it is only necessary, when it is desired to fill the tank 6, for the operator to open air valve 13, the air pressure in the reservoir being sufficient to force the gasoline up pipe 4 and into the dispensing tank, and when the tank has been filled or partly filled further supply can be stopped by cutting off the air.

It is evident that numerous changes might be resorted to in the relative arrangement of parts shown and described without departing from the spirit and scope of my invention. Hence I would have it understood that I do not wish to confine myself to the exact construction and arrangement of parts shown and described, but

Having fully described my invention what I claim as new and desire to secure by Letters-Patent, is:—

1. In a gasoline dispensing apparatus, the combination of a main tank, a dispensing tank, a three way coupling, a continuously open pipe leading from the main tank to the coupling, a continuously open pipe leading from the coupling to the dispensing tank, an air pipe leading from a source of supply to the three way coupling and discharging into the latter, a valve in said air pipe, a discharge pipe from the dispensing tank and a valve in said latter pipe.

2. In a gasoline dispensing apparatus, the combination of a main tank, a dispensing tank in a plane above the main tank, a three way coupling, a continuously open pipe leading from the main tank to the coupling, a continuously open pipe leading from the coupling to the dispensing tank, an air pipe leading from a source of air supply into the three way coupling and discharging into the latter in line with the open end of the pipe leading to the dispensing tank, a valve in said air pipe, a discharge pipe from the dispensing tank and a valve in said pipe.

3. In a gasoline dispensing apparatus, the combination of a main tank, a dispensing tank in a plane above the main tank, a three-way coupling, a continuously open pipe leading from the main tank to the coupling, a continuously open pipe leading from one end of the coupling to the dispensing tank, an air pipe leading from a source of compressed air supply and terminating in the three-way coupling in a plane above the discharge end of the pipe from the main tank and in line with the pipe leading to the dispensing tank, a discharge pipe from the dispensing tank, a valve in said discharge pipe and a valve in the air pipe.

4. In a gasoline dispensing apparatus, the combination of a main tank, a dispensing tank in a plane above the latter, a stand for the dispensing tank, a three way coupling, a continuously open pipe leading from the main tank to the coupling, a continuously open pipe leading from the latter to the dispensing tank, a discharge pipe from the latter, a pipe leading from a source of air under pressure and terminating within the coupling in a plane with the pipe leading to the dispensing tank, the said air pipe passing up into the stand for the dispensing tank and provided therein with a valve, and a valve in the discharge pipe of the dispensing tank.

5. In gasoline dispensing apparatus, the combination of a main tank, a dispensing tank, a three-way coupling intermediate the two tanks, a continuously open pipe leading from the main tank to the coupling, a continuously open pipe leading from the latter to the dispensing tank, an air pipe leading from a source of compressed air supply and terminating in the three way coupling below and in the vertical plane of the open end of the pipe leading to the dispensing tank, a discharge pipe from the dispensing tank, a valve in the latter, and a valve in the air pipe, the said valves being within a casing below the dispensing tank and a door to said casing whereby the valves will be concealed when the door is closed.

6. In a gasoline dispensing apparatus, the combination of a dispensing tank, a supply pipe passing up into the latter and terminat-

ing near the top thereof, a fixed depending valve seat carried by the top of the tank, a float having a central opening for the supply pipe and making a snug fit with the latter so as to prevent the passage of any appreciable amount of gasoline between the pipe and float and a fixed valve on the top of the float and adapted when the latter has reached its highest point to contact with the fixed valve seat at the top of the dispensing tank and cut off the supply of gasoline to the tank.

7. In a gasoline dispensing apparatus, the combination of a dispensing tank, a supply pipe passing up into the latter and terminating near the top thereof, a seat for a valve adjustably secured to the top of the dispensing tank, a float in the dispensing tank having an opening through the same for the passage of the supply pipe and a valve fixed on said float adapted to contact with said

adjustable seat for automatically cutting off the supply of gasoline.

8. The combination of a main tank, a graduated transparent dispensing tank, a three-way coupling, a continuously open pipe leading from the main tank to the coupling, a continuously open pipe leading from the latter to the dispensing tank, a pipe leading from a source of compressed air and discharging into the coupling below the open end of the pipe leading to the dispensing tank, a discharge pipe from the dispensing tank, a valve in said discharge pipe and a valve in the air pipe.

In testimony whereof, I have signed this specification in the presence of two subscribing witnesses.
